THROTTLE OPERATING MEANS FOR LOCOMOTIVES

Application filed May 21, 1928. Serial No. 279,451.

This invention relates to throttle operating means for locomotives. With locomotives using high pressure steam, in accordance with the present day practice, it is quite difficult for the engineman to manipulate the throttle lever manually to open or otherwise set the throttle valve against the high pressure of the steam, the exertion of great physical effort being required to manipulate the throttle lever of the high pressure locomotives.

The principal object of the present invention is to provide a new and improved construction for operating the throttle valve by power means and to so construct such power means that it will be positive and certain in its action while at the same time of sturdy, simple construction capable, not only of being manufactured at a relatively low cost, but also capable of being readily installed upon locomotives.

Another object is to provide a new and improved construction for the throttle lever.

The above and other objects of the present invention will appear more fully from the following more detailed description and by reference to the accompanying drawings forming a part hereof, wherein Fig. 1 is a side elevation, partly in section, of a throttle lever constructed in accordance with the principles of the present invention; Fig. 2 is a section on the line 2—2 of Fig. 1; Fig. 3 is a section on the line 3—3 of Fig. 1; Fig. 4 is a central longitudinal section through the improved power means for operating the throttle valve; Fig. 5 is a section on the line 5—5 of Fig. 4; Fig. 6 is a section on the line 6—6 of Fig. 5; Fig. 7 is a side elevation, on a smaller scale, of the power means shown in Fig. 6, and illustrating the connection of said means to the throttle valve shaft, and Fig. 8 is a diagrammatic side view showing the manner in which the invention is installed upon a locomotive.

The present invention, briefly, consists of a piston and cylinder to which air is admitted from the main air tank of the locomotive and the piston being held normally in a position corresponding to the closed position of the throttle valve by means of a coiled compression spring. A plurality of

valves for the admission of compressed air to the cylinder are caused to be automatically operated under the control of the throttle lever. The latter is so constructed and so connected to the power means that, upon initial movement of the lever, a main valve is caused to be opened to permit the air to flow into the cylinder and to actuate the piston, against the action of the spring above referred to, for causing the throttle valve to be opened. 55 The throttle lever and its connections to the power means are so arranged that there is a lag of the movement of the power means behind the movement of the throttle lever, whereby, when the movement of the throttle lever is stopped, certain parts which comprise the power means overhaul, or catch up to, the members actuated by the movement of the throttle lever, and the valves, which control the admission of air to the cylinder of 60 the power means, are automatically actuated to check the motion of the piston and, when the latch of the throttle lever is locked, to hold the parts in set position. Continued 65 motion of the throttle lever will cause the power means to again become operative until the throttle lever is again held stationary and the said certain parts of the power means again overhaul or catch up to the movement of the lever. The connection of 70 the lever to the power means is also so arranged that should the power means be inoperative, for any reason whatsoever, such, for example, as the failure of the air, the 75 throttle valve may be moved solely by the mechanical operation of the throttle lever in the same direction as for causing the power means to operate. 80

In Figs. 1, 2 and 3 of the drawings the numeral 10 indicates a throttle lever which is pivotally supported at its upper end upon the pivot pin 11, mounted on a bracket 12 secured to any suitable stationary support, such as the side wall of the locomotive fire box. 85 At its lower end the lever 10 has pivotally supported thereto, by means of the pivot pin 13, a handle lever 14, having at its lower end a hand grip 15. The upper end of the hand lever 14, is provided with a cam slot 16 through which passes a headed pin 17. The 90

body of the pin 17 passes through an elongated vertical slot 18 provided in the lower end of the lever 10, and said pin 17 at its inner end is screwthreaded into the body of a latch 19. At its upper end, the latch 19 is provided with a plurality of teeth 20 for engagement with the teeth 21 of a quadrant bar 22, the latter being of the type usually employed for use with locomotive throttle levers. The latch 19 is slidably mounted in a guideway formed by one flat face of the lever 10 and a retaining plate 23, the latter being held upon the lever 10 by means of the bolt 24 which passes through an elongated slot 25 provided in the latch 19. It will be noted that the bolts 17 and 24 co-operate with the vertically extending slots 18 and 25 to insure movement of the latch 19 longitudinally of the lever 10 without permitting any swinging or pivotal movement of said latch upon either of the bolts as a pivot. Mounted in the slot 18, is a coiled compression spring 26, the lower end of which abuts against the lower end of the slot 18, and the upper end 25 of said spring abuts against the pin 17 and serves to hold said pin and said latch 19 normally in their uppermost position of travel, with the teeth 20 of the latch in meshing engagement with the teeth 21 of the 30 quadrant.

The handle lever 14 is in the form of a bell crank, as clearly shown in Fig. 1 and has a lateral arm 14^a, to the outer end of which is pivotally connected, by means of a pin 27, a small connecting rod 28. At its upper end, the link 28 is pivotally connected to one arm of a bell crank 29. The bell crank 29 is pivotally supported within the jaws of a yoked portion 10^a of the lever 10, by means of a pin 30, the outer ends of which are supported in the yoke jaws, and the central part of which passes through the bearing boss 29^a of the bell crank 29.

The other arm of the bell crank 29 has 45 pivotally secured to it, the rear end of a solid connecting rod 31, which extends longitudinally from the cab of the locomotive along the side of the engine to a point adjacent to the throttle valve. Said rod 31 passes freely 50 through a hollow operating rod 32, the rear end of which has connected thereto a yoke member 33. The jaws of the yoke member 33 straddle the yoke portion 10^a and are secured to the portion 10^a by means of a pair of studs 55 or pins 34 which project laterally from the outer faces of the portion 10^a.

It will be seen from the above description that, when the hand lever 14 is swung upon its pivot 13, in the direction of the arrow in 60 Fig. 1, the arm 14^a of said lever will cause link 28 to swing the bell crank 29 in a clockwise direction and thereby draw the rod 31 rearwardly of the locomotive or from right to left as seen in Fig. 1 of the drawings. If 65 the handle lever is so swung, the engagement

of the cam slot 16 of said lever with the pin 17 will cause said pin to be moved downwardly. It will be remembered that the pin 17 has its inner end fixed in the latch 19 and therefore when the pin is moved downwardly, as just described, the latch 19 will be moved downwardly to cause the teeth 20 at the upper end thereof to be moved out of meshing engagement with the teeth 21 of the quadrant. The parts above described represent that the portion of the mechanism which, as shown in Fig. 8, is located in the cab of the locomotive.

The parts which are located adjacent to the throttle valve shaft and which comprise the power means of the installation will now be described. The invention has been shown as applied to a locomotive of the type using superheated steam and in which a throttle valve shaft extends transversely of the locomotive boiler and which shaft is rotated to operate a plurality of throttle valves which govern the admission of steam to the engine cylinders. This type of throttle valve and shaft is well known in the art and the detailed constructions of the shaft and valves have not been shown in the drawings. In Fig. 7 of the drawings the numeral 35 indicates such a throttle valve shaft, the outer end of which, as shown, is of square construction and fits within one end of an actuating arm 36. The other end of the arm 36 is pivotally connected to a short connecting link 37. The front end of the link 37 is pivotally connected with a sleeve 38, screwed or otherwise rigidly fixed upon the end of a piston rod 39, to the other end of which rod is connected a piston 40. The piston 40 is mounted within a cylinder 41 suitably secured to the boiler shell, or any other suitable stationary support, preferably at a point adjacent to the throttle valve shaft 35.

For convenience in assembling the parts, the rod 31 is made in two sections, a short front section and a longer rear section, which sections are connected together, as shown in Fig. 7, by means of a turn buckle 42. The hollow rod 32 is also made in two section secured together by means of a turn buckle 43, which, as shown in Fig. 7, has a central offset connecting bar which spans the turn buckle 42.

As clearly shown in Fig. 4 the hollow rod 32 passes freely through the center of the hollow piston rod 39 and terminates at its front end in an annular shoulder or flange 32^a. This flange 32^a is located within a recess or pocket 32^b formed in the front of the piston 40, the front opening of said pocket being closed by a packing retaining plate 40^b and packing 40^c. The plate 40^b has a central boss 40^d which projects through the packing so that the rear wall of said boss is adapted to abut the front end of the hollow rod 32. The solid rod extends at its front end to a

point adjacent to the shouldered front end of the hollow rod 32. Located within the cylinder 41 is a coiled compression spring 44 which encircles the piston rod 39 and abuts at its rear end against the rear wall of the cylinder. The front end of the spring 44 engages a follower plate 45, which plate is held by said spring against the heads of the bolts 46 which secure the piston rod 39 to the piston 40. The spring 44 normally holds the parts in the position shown in Figs. 4 and 7 of the drawings with the piston 40 in its innermost position of travel. Compressed air is admitted into the interior of the cylinder 41 through a pipe 47 connected to the cylinder at a point just forwardly of the rear end of the piston. Air from this pipe flows into the space defined between the inner walls of the cylinder and the reduced central portion 40^a of the piston. This space communicates through an elongated slot or port 48 in the upper face of the piston with a conduit 49. A valve 50 slidably mounted in the piston, and to one side of the center thereof, is normally held by the action of a spring 51 to shut off communication between the conduit 49 and the slot 48. The conduit 49, as more clearly shown in Fig. 6 of the drawings, extends laterally and forwardly, and communicates through a check valve 52 with a space 53, defined between the cylinder head 54 and the front end of the piston 40. The check valve 52 is mounted within a valve cap 55 secured to the piston by means of a small nipple 56; said valve cap 55 is provided with a plurality of apertures 57 through which the air passes to the space 53.

The space 53 is also in communication by means of a plurality of inclined passage ways 58 with a small valve chamber 59 in which is seated a valve 60 having an extension 61 which projects rearwardly and terminates a short distance from the front end of the solid rod 31. The valve 60 is normally held in the closed position by means of a small spring 62 which bears at one end against the valve and at its other end against a valve cap or bonnet 63 screwed into the front wall of the piston.

The front end of the solid rod 31 is provided with a bore 64 which is adapted to communicate at its front end with the space 53 when the valve 60 is opened. Said bore at its rear end is provided with a lateral opening 65 adapted to communicate through a pair of aligned openings 66, provided in the hollow rod 32 and piston rod 39, with the space to the rear of the piston 40 and with atmosphere through opening 96.

The manner in which the device operates is as follows: Let it be assumed that air under pressure is being delivered to the interior of the cylinder 41 through the pipe 47, and that the parts are in the position shown in Fig. 4. This figure of the drawings il-

lustrates the parts in their normal inoperative position. If now the engineman swings the handle lever 14 in the direction of the arrow shown in Fig. 1, the first results of such swinging will be to disengage the teeth 79 of the latch 19 from the teeth of the quadrant 22 and, through the connecting rod 28 and bell crank 29, to move the solid rod 31 rearwardly. During this first portion of the swinging movement of the hand lever 14, said lever merely pivots upon the throttle lever 10, without producing any movement of the latter. The length of the solid rod 31, relatively to the length of the hollow rod 32, is such that as shown in Fig. 4 the front end 75 of the solid rod is normally out of engagement with the stem 61 of the valve 60. By the time the teeth of the latch 19 are disengaged from the teeth of the quadrant 22 the front end of the solid rod will be moved further away from the stem 61. If, after the latch 19 is disengaged, the engineman continues to swing the handle 14 in the direction of the arrow of Fig. 1, this movement will be communicated to the throttle lever 10 which 80 may then also be swung in a clockwise direction and a rearward pull (i. e. from right to left) will therefore be exerted on the hollow rod 32.

It will be seen from Fig. 4 that the shoulder 95 32^a at the end of the hollow rod is in engagement with the stem of the valve 50 so that, as the swinging movement of the lever 10 occurs and also the rearward movement of the hollow rod 32, the engagement of the 100 shoulder end 32^a of said hollow rod with the end of the stem of the valve 50 will cause said valve to be lifted off its seat. When this occurs, the air supplied through the pipe 47, will pass through the conduit 49, opening the check valve 52, and flowing to the space 53. The air entering the space 53 will build up a pressure ahead of the front face of the piston 40 and will move the piston from the right toward the left. The piston 110 rod 39, being connected to the throttle valve shaft 35 through the parts 36, 37 and 38, will cause said valve shaft to be rotated in a counter-clockwise direction so as to move the throttle valve towards its open position. 115

The engineman will move the lever 10 to the proper position to obtain the desired throttle opening and in so doing, it will be necessary for him to exert only the physical effort necessary to overcome the inertia of 120 the rods 31, 32 and to move the valve 50 off its seat. After the valve 50 has been opened, the movement of the piston is accomplished by the pressure of the air admitted to the space 53, and, as the piston moves rearwardly, 125 its motion may be accompanied by a similar movement of the throttle lever, the engineman being required to exert merely sufficient pull upon the throttle lever to keep the valve 50 opened. When the throttle has been open- 130

ed to the desired extent, the handle lever 14 is swung backwardly upon the pivot 13 thereby permitting latch 19 again to be engaged with the quadrant.

- 5 During the movement of the parts as above described, and after the opening of the valve 50, no relative movement between the piston 40 and the hollow rod 32 will occur as long as the engineman exerts but a slight pressure 10 upon the handle sufficient to cause the rods 31 and 32 to follow the movement of the piston. When the handle 14 is moved slightly backward to lock the latch 19 and thereby to hold the lever 10 in set position, relative 15 movement will then take place between the piston 40 and the rod 32, the pressure of the shoulder 32^a against the end of the stem of the valve 50 being released and the end of the valve moving slightly out of contact with 20 said shoulder so as to permit the valve 50 to shut. This will interrupt the flow of the air through the conduit 49; check valve 52 will then close and the air trapped in the space 25 53 will hold the piston in its set position against the pressure of the spring 44.

It will be seen from an inspection of Fig. 4 of the drawings, which shows the normal relative positions of the parts of the fluid pressure motor when such parts are at rest 30 with the latch 19 engaged in locked position, that the valve 50 is closed and that the end of its stem just clears the rear wall of the flange 32^a, while the front end of the hollow rod 32 is in contacting engagement with the 35 rear face of the boss 40^a of the packing retaining plate 40^b. The above parts are so dimensioned that a limited amount of free or lost motion is provided in the pocket 32^b for the flange 32^a, such motion being merely enough 40 to permit the unseating of the valve 50. If after the throttle lever has been set and latched in position, leakage of air from the space 53 occurs and the air pressure in such space drops sufficiently to permit the spring 45 44 to move the piston 40 forwardly, a very slight forward movement will result in the opening of the valve 50 and the admission of more air to the space 53 to restore the pressure. Should the pressure in the space 53 50 tend to increase beyond the amount necessary to maintain the piston at the desired setting against the pressure of the spring 44, the abutment of the rear wall of the boss 40^a with the front end of the hollow rod 32 prevents further rearward movement of the 55 piston, it being remembered that the rod 32 is held stationary by the locking engagement of the latch 19 with the quadrant 22. The extent of the movement of the piston 60 just described is of course limited by the extent of lost motion provided by the pocket 32^b for the flange 32^a which it will be seen is quite small, therefore although an alternating forward and backward movement of the 65 piston may occur as the result of the auto-

matic compensation for leakage from the space 53 the movement is of such slight extent that no appreciable change in the setting of the throttle is effected.

When the engineman desires to close the 70 throttle the handle lever 14 is moved in a reverse direction to that above described, the latch 19 being disengaged as before by the initial swinging movement of the handle lever, except that when the handle lever was 75 moved in the direction of the arrow shown in Fig. 1, the left hand side of the slot 16 was operative to produce the sliding movement of the latch to disengaged position, while in the reverse movement of the handle lever the 80 right hand portion of the cam slot 16 obviously will function to cause the disengagement of the latch. The reverse swinging movement of the handle lever will cause the 85 arm 14^a of the lever 14 to pull the bell crank 29, through the rod 28, in a counter-clockwise direction, thus moving the solid rod 31 forwardly or from left to right. This movement of the solid rod 31 obviously is a movement thereof relatively to the hollow rod 32 90 and to the piston 40. The end of the solid rod 31 is therefore brought into engagement with the extension 61 of the valve 60, thus causing the valve 60 to be raised off its seat. This permits the air, trapped in the space 53, to 95 escape through the passages 58, past the valve 60 and into the bore 64 in the end of the solid rod 31. The air escapes from the bore 60 through the apertures 65, 66 and 96. The forward movement of the rod 31 is followed 100 immediately by a similar movement of the hollow rod 32 to cause the shoulder 32^a at the front end of the latter rod to be moved out of engagement with the stem of the valve 50 thus permitting the valve 50 to close and shut 105 off the air flow through the conduit 49. The air pressure in the space 53 obviously is therefore reduced, and the piston 40 begins to travel under the influence of the spring 44 from left to right. The engineman follows up the movement of the piston by continuing the reverse movement of the throttle lever 10, as will be readily understood, until said lever has been again set to any desired 110 position of throttle opening or in the closed 115 throttle position.

If there should be a failure of the air pressure it is possible for the engineman to move the piston 40 by the exertion of sufficient physical effort to compress the spring 44. While a much greater effort will be required on the part of the engineman to move the piston 40 against the spring 44 than is required when the piston is moved by the air pressure the parts are so constructed and arranged that not only is the manual opening of the throttle possible, but the motion of the engineman in so opening it is the same as when the piston is moved by the air pressure. While the engineman will be required to exert 125 120

a greater force to accomplish the opening of the throttle in case the power means fails to function it is to be noted that the closing of the throttle is accomplished by the force of the spring 44. As a quick closing of the throttle is frequently necessary to avoid trouble the advantage of providing the spring 44 or any equivalent device will be apparent because the closing movement is always assisted by the spring pressure irrespective of the pressure conditions in the air lines. It will be seen that the installation herein disclosed is not solely dependent upon the functioning of the power operated means but that, in case of emergency, the throttle can be opened or closed just as if the power means were not provided.

While the installation illustrated and described herein exemplifies a satisfactory example, constructed in accordance with the principles of the invention, it will be understood that such principles are not limited to the specific constructional details of the parts shown and described, but that many changes, variations and modifications may be resorted to without departing from the spirit of the invention.

I claim:

1. In a locomotive, a throttle valve and fluid pressure actuated means connected therewith, an inlet valve and an exhaust valve for controlling the operation of said fluid pressure actuated means, a throttle lever, operating means mounted on said lever and movable relatively thereto, and a pair of telescopically arranged connections to said lever and operating means respectively movable one within the other for actuating said valves to admit and exhaust pressure fluid to and from said fluid pressure actuated means whereby the latter is selectively operated to open and close said throttle valve.

2. In a locomotive, a throttle valve, fluid pressure actuated means including a piston connected with said throttle valve, an inlet valve and an exhaust valve carried by said piston for governing the actuation of said fluid pressure means, a manually operated lever consisting of two relatively movable sections, a connection to one section of said lever for controlling the operation of said inlet valve whereby pressure fluid is admitted to said fluid pressure actuated means to operate said piston and open said throttle valve, a second connection to the other section of said lever for controlling the operation of said exhaust valve whereby said pressure fluid is exhausted from said fluid pressure actuated means, said connections being telescopically arranged one within the other, and means for operating said piston in a return direction to close said throttle valve, as said exhaust valve is operated.

3. The combination with the throttle valve of a locomotive, of a cylinder and a fluid

pressure actuated piston therein, means connecting said piston to said throttle valve, an inlet valve carried by said piston for admitting fluid under pressure to said cylinder, a release valve carried by said piston for permitting escape of fluid from said cylinder, a manually operable lever located at a point remote from said cylinder, and a pair of telescopically arranged members connected to said lever and operatively associated, one with said inlet valve and the other with said release valve.

4. The combination with the throttle valve of a locomotive, of a cylinder and a fluid pressure actuated piston therein, means connecting said piston to said throttle valve, an inlet valve carried by said piston for admitting fluid under pressure to said cylinder, a release valve carried by said piston for permitting escape of fluid from said cylinder, a spring for urging said piston in a direction to close said throttle valve, a manually operable throttle lever and a pair of telescopically arranged rods connected thereto, one of said rods being operatively associated with the inlet valve and the other with said release valve.

5. The combination with the throttle valve of a locomotive, of a cylinder and a fluid pressure actuated piston therein, means connecting said piston with said throttle valve, an inlet valve carried by said piston for admitting fluid under pressure to said cylinder to actuate said piston in a direction to open said throttle valve, a spring for urging said piston in the opposite direction, a release valve for permitting the escape of fluid from said cylinder and for permitting said spring to move said piston when said release valve is open, a throttle lever and means connected thereto for actuating said inlet valve and release valve, said means including a pair of relatively movable telescopic members extending axially of said piston in slidable relation thereto and having a lost motion connection with said piston whereby, after a predetermined extent of movement of said means relatively to said piston to actuate said inlet valve, said means may become operative for permitting said piston to be moved manually against the action of said spring.

6. The combination with the throttle valve of a locomotive, of a cylinder and a fluid pressure actuated piston therein, means connecting said piston with said throttle valve, a normally closed inlet valve carried by said piston for admitting fluid under pressure to said cylinder to actuate said piston in a direction to open said throttle valve, a spring for urging said piston in the opposite direction, a throttle lever, a normally closed release valve carried by said piston for permitting the escape of the fluid from said cylinder thereby to allow said spring to actuate said piston, a throttle lever, and a pair of connec-

tions therefrom to said inlet and release valves for opening the same in inverse relation, said connections including a pair of relatively movable telescopic members extending axially of said piston in slidable relation thereto and having a predetermined amount of lost motion therein whereby movement of said throttle lever in one direction will insure the closing of said release valve before said inlet valve is opened and movement of said lever 10 in the opposite direction will insure the closing of said inlet valve before said release valve is opened.

7. The combination with the throttle valve of a locomotive, of a cylinder and a fluid pressure actuated piston therein, means connecting said piston with said throttle valve, an inlet valve carried by said piston for admitting fluid under pressure to said cylinder to actuate said piston in a direction to open 15 said throttle valve, a spring for urging said piston in the opposite direction, a release valve carried by said piston for permitting the escape of fluid from said cylinder thereby to allow said spring to actuate said piston, a throttle lever including a latch movably mounted on said lever and means to actuate said latch, a connection from said lever for actuating said inlet valve and means including an elongated rod extending axially of said 20 piston and operatively associated with said latch actuating means and said release valve for operating the latter.

8. The combination with the throttle valve of a locomotive, of fluid pressure actuated means operatively connected with said throttle valve, a manually operable lever device, a pair of valves movable with said fluid pressure actuated means, a pair of telescopically arranged members connected to said lever device and relatively movable thereby to actuate said valves relatively to said fluid pressure means in predetermined sequence whereby the latter is operated to open and close said 25 throttle valve, means for locking said lever device in different adjusted positions corresponding to different set positions of said throttle valve opening, and means for automatically preventing variation in the extent 30 of throttle opening as a result of leakage to or from said fluid pressure means when said lever device is locked in adjusted position.

9. In a throttle actuating device, a pivoted main lever and a toothed quadrant, a hand lever pivotally mounted on said main lever, a latch movably mounted on said main lever for engagement with said quadrant, cam means actuated by movement of said hand lever relatively to said main lever for moving 35 said latch out of engagement with said quadrant, said cam means including stops for preventing relative movement between said hand lever and main lever after said latch is disengaged, whereby upon further movement 40 of said hand lever, said main lever and hand

lever are swung in unison, a lateral arm projecting from one side of said hand lever, a bell crank mounted on said main lever, a connecting link pivotally connected with said arm and said bell crank whereby the latter is actuated by a relative movement of said hand lever, and fluid pressure operated means including valves connected with and adapted to be individually operated in predetermined sequence by said hand lever and main lever respectively. 70

10. In a locomotive, a throttle valve, fluid pressure operated means including a pair of valves movable therewith and connected with said throttle valve for actuating it by power, controlling devices for said means and valves, a throttle lever, a pair of telescopically arranged connections from said lever to said controlling devices for actuating said valves to cause said fluid pressure means to operate said throttle valve when said lever is moved, said connections and fluid pressure means including parts adapted to engage each other for permitting the direct manual actuation of said throttle valve by said lever 80 upon failure of the fluid pressure means to function, the movement of said lever for effecting the manual actuation of said throttle valve being similar in direction and extent to the movement of said lever to effect 85 a corresponding movement of the throttle valve by the fluid pressure means. 90

11. In a locomotive, a throttle valve, fluid pressure operated means for operating said throttle valve and including a piston carrying two valves, resilient means for normally urging said piston and two valves in a direction to shift said throttle valve towards its closed position, a throttle lever, and controlling devices including a pair of telescopic connections actuated by said throttle lever to cause said pressure operated means to open said throttle valve when said lever is moved in one direction, and when said lever is moved in the opposite direction to cause said resilient means to become operative to close 100 said throttle valve. 105

12. In a locomotive, a throttle valve, fluid pressure operated means connected with said throttle valve and including two valves, a throttle lever, and connections including a pair of telescopically arranged members from said lever to said fluid pressure means for controlling the operation of the latter via 110 said two valves, said connections including parts adapted to engage each other for enabling the throttle valve to be actuated manually upon failure of the fluid pressure means to function. 115

In testimony whereof I have hereunto set 120 my hand.

NEAL T. MCKEE.
